(57) **CLAIM**

The ornamental design for a pizza container tray as shown and described.

DESCRIPTION

FIG. 1 is a top view of a pizza container tray showing our new design;

FIG. 2 is a bottom view thereof;

FIG. 3 is a right-side view thereof;

FIG. 4 is a left-side view thereof;

FIG. 5 is a front view thereof; and,

FIG. 6 is back view thereof.

The broken lines in the drawings depict portions of the pizza container tray that form no part of the claimed design.
